UNITED STATES PATENT OFFICE

ROLLAND S. FULTON, OF DETROIT, MICHIGAN, ASSIGNOR TO NATIONAL TIME & SIGNAL CORPORATION, OF DETROIT, MICHIGAN, A CORPORATION OF MICHIGAN

TELEPHONE CIRCUIT AND TRANSFORMER THEREFOR

Application filed November 5, 1931. Serial No. 573,118.

This invention relates to telephone circuits and transformers therefor and the object of the invention is to provide a telephone circuit including a transformer in which the primary is connected to a source of alternating current supply and the secondary is divided, a portion of the secondary carrying alternating current for the telephone ringing circuit and the other portion of the secondary being connected through rectifiers to provide direct current for a telephone speaking circuit.

Another object of the invention is to provide a transformer in which both alternating and direct current are produced from the secondary for operating the ringing circuit and speaking circuit of a telephone system.

Another object of the invention is to provide a transformer adapted for connection to an A. C. in-put and having the out-put connected to provide alternating current for telephone bell ringing and direct current for a telephone speaking circuit, the direct current being produced from the alternating current by rectifying the alternating current wave.

Another object of the invention is to provide a complete instrument for producing two types of current from the same alternating current source.

These objects and the several novel features of the invention are hereinafter more fully described and claimed and the preferred form of construction by which these objects are attained is shown in the accompanying drawing in which—

Fig. 1 is a view showing a diagrammatic transformer circuit embodying my invention.

Fig. 2 is a perspective view of the casing containing the transformer and rectifier units.

Fig. 3 is a section taken on line A—A of Fig. 2.

As shown in Fig. 1 the alternating in-put circuit is represented by the wires 1 and 2. A fuse 3 is connected in the wire 1 and this wire is provided with a terminal 4. The wire 2 is provided with a switch 5 and this

wire is connected to one end of the primary 6 of the transformer. This primary is provided with leads to contact points 7, 8 and 9 and a wire 10 connected to the contact 4 may be connected to the contacts 7, 8 and 9 to connect more or less of the transformer primary into the circuit. The secondary consists of two parts, a part 11 in which alternating current is induced for a telephone bell ringing circuit and parts 12 and 13 in which alternating current is induced and carried to the rectifiers 14. The part 11 of the secondary is provided with one lead 15 and two other leads 16 and 17 which are connected so as to carry off a twelve or eighteen volt current when the in-put current is 110 volts, the wire 16 carrying a twelve volt current and the wire 17 carrying an eighteen volt current. The portion 12 of the secondary is connected to the lower rectifier 14 by means of the wires 18 and 19 and the part 13 of the secondary is connected to the upper rectifier 14 by the wires 20 and 21. A wire 22 is also provided connecting the two rectifiers. With this arrangement the two sides of the alternating current wave are carried to the rectifiers and the rectifiers are connected in series across the circuit represented by the wires 23 and 24.

Two choke coils 25 are connected in the circuit 24 and a series of high capacity condensers 26, 27 and 28 are connected across between the circuit wires 23 and 24 and a volt meter 29 is also connected between these wires. This is a standard rectifier circuit for transforming alternating current to direct current and the out-put of this circuit is utilized for operating the speaking circuit of a telephone system. The device is particularly adapted for use with small telephone systems such as the inter-communicating systems utilized in large factories, manufacturing plants and apartment houses.

For convenience, the several instrumentalities are mounted in a compact rectangular casing shown in Figs. 2 and 3. The lower half of the casing contains the high capacity condensers 26, 27 and 28 and is provided with a horizontal partition 30

shown in Fig. 3 above the condensers and extending horizontally across the casing. Mounted on the partition 30 is the transformer 31, the coils of which are represented by numerals 6, 11, 12 and 13 in Fig. 1. The choke coils 25 are mounted on the partition 30 with the cores of the choke coils extending transversely to the core of the transformer 31 to prevent interference of the magnetic fields. A panel 32 is mounted on the base 30 and carries the fuse 2, switch 5 and volt meter 29 and mounted on the panel 32 above these instruments are the rectifiers 14. The several instruments are connected together in the casing to provide the circuit shown in Fig. 1 and it is only necessary to connect the device to a suitable source of current supply and connect the out-put circuits to the telephone ringing circuit and to the telephone speaking circuit at which time complete current is provided for the entire telephone system.

The primary 6 is tapped as shown in Fig. 1 and the movable circuit wire 10 may be connected to any of these taps 7, 8 or 9. By moving the circuit wire 10 to the various taps the direct current out-put from the rectifier circuit may be varied and while this will also vary the out-put for the telephone ringing circuit a slight variation of this out-put circuit will not have a detrimental effect. The taps 7, 8 and 9 also provide a means for varying the primary according to the in-put alternating current voltage. For instance, if the in-put current is 120 volts, the wire 10 may be connected to the tap 7, if the in-put current is 115 volts, the wire 10 may be connected to the tap 8 and if the in-put current is 110 volts, the wire 10 may be connected to the tap 9 so as to produce the desired out-put voltage from the rectifiers. It will thus be seen that the tapped primary provides a means for adjusting the primary in accordance with the A. C. in-put voltage and at the same time if the out-put voltage from the rectifiers is too low or too high the out-put voltage may be varied by connecting the A. C. in-put to the different taps 7, 8 and 9. This arrangement of a tapped transformer primary to vary the out-put A. C. and D. C. voltage for a telephone circuit is believed to be new and to provide features not heretofore known. From the foregoing description it becomes evident that the device is very simple and efficient in operation, provides a compact mechanism for inter-communicating telephone systems, is adjustable to vary the out-put voltage and provides a device which accomplishes the objects described.

Having thus fully described my invention, its utility and mode of operation, what I claim and desire to secure by Letters Patent of the United States is—

1. In a telephone circuit, a casing, a partition mounted intermediate the top and bottom of the casing, a transformer mounted on the partition and having a variable primary adapted to be connected to an alternating current in-put circuit, the secondary of the transformer being divided and having a portion providing alternating current for a telephone ringing circuit, a panel mounted on the partition, the casing being provided with an opening through which the panel is exposed to view, a series of rectifiers mounted on the panel, a portion of the secondary being connected to the rectifiers, a series of high capacity condensers mounted in the lower portion of the casing beneath the partition and a series of choke coils mounted on the partition, the rectifiers being connected to the condensers and choke coils to rectify the transformed current for a telephone speaking circuit and a volt meter mounted on the panel and connected in the telephone speaking out-put circuit to give voltage readings thereof. 70

2. In a transformer for use with alternating current to provide alternating current for a telephone ringing circuit and direct current for a telephone speaking circuit, a casing, a series of high capacity condensers mounted in the lower portion of the casing, a horizontal partition intermediate the top and bottom of the casing and providing a cover for the condensers, a transformer mounted on the partition, a vertical panel mounted on the partition, the casing being provided with an opening adjacent the panel to expose the panel to view, rectifier elements mounted on the panel, a fuse mounted on the panel and connected into the alternating current in-put circuit and a volt meter mounted on the panel to give the readings of the telephone speaking out-put circuit. 90

3. In a transformer for use with alternating current to provide current for telephone ringing and telephone speaking circuits, a casing, a series of high capacity condensers mounted in the lower portion of the casing, a horizontal partition extending across the casing above the condensers, a transformer mounted on the partition, a choke coil mounted on the partition with the core extending at a right angle to the core of the transformer, a panel mounted on the partition, a rectifier mounted on the panel and a volt meter mounted on the panel to give the voltage readings of the telephone speaking out-put circuit. 110

In testimony whereof I sign this specification.

ROLLAND S. FULTON.
